UNITED STATES PATENT OFFICE.

HUSTON TAYLOR, OF DETROIT, MICHIGAN.

DESIGN FOR A BUMPER IMPACT BAR.

Application filed January 6, 1925. Serial No. 11,939. Term of patent 14 years.

To all whom it may concern:

Be it known that I, HUSTON TAYLOR, a citizen of the United States, residing at Detroit, in the county of Wayne and State of Michigan, have invented a new, original, and ornamental Design for Bumper Impact Bar, of which the following is a specification, reference being had to the accompanying drawing, forming a part thereof.

In the drawing,
Fig. 1 is a plan view of a bumper impact bar showing my new design, and
Fig. 2 is a front elevation of the same.

I claim:

The ornamental design for a bumper impact bar, substantially as shown.

HUSTON TAYLOR.
